COMBINED BARBECUE MACHINE AND FOOD WARMER

Robert G. Wilson, Greenville, S.C.

Application August 6, 1956, Serial No. 42,521

Term of patent 14 years

(Cl. D81—10)

Fig. 1.

Fig. 2.

Fig. 1 is a front perspective view of a combined barbecue machine and food warmer embodying my new design; and

Fig. 2 is a rear perspective view, illustrating the warmer compartment with the door open and with two trays removed.

I claim:

The ornamental design for a combined barbecue machine and food warmer, substantially as shown.
